UNITED STATES PATENT OFFICE.

JAMES E. ECKERSLEY, OF ABERDEEN, WASHINGTON, ASSIGNOR OF ONE-HALF TO
ALEXANDER POLSON, OF HOQUIAM, WASHINGTON.

KNIFE BAR.

Application filed August 19, 1927. Serial No. 214,186.

The object of my invention is to provide a knife bar, and its mounting, for wood slicing machines (shingle, shooks and veneer) which will make the desired cuts with a minimum of power and without liability of dragging undercut fibers through the timber thereby eliminating the possibility of breaking the grain and the other fibers ahead of it and shattering the stock; and with these and other objects in view my invention consists of the parts and combination of parts as will be hereinafter more fully set forth.

In the drawings:

Figure 1 is a front elevation of the knife bar and its mounting.

Figure 2 is a top plan view of the same.

Figure 3 is a section on the line 3—3, Figure 1, looking in the direction of the arrows.

Figure 4 is a sectional view on the line 4—4, Figure 3, looking in the direction of the arrow.

Figure 5 is a section on the line 5—5, Figure 4 looking in the direction of the arrows.

Figure 6 is a front elevation of another embodiment of my invention.

Figure 7 is a top plan view of Figure 6.

Figure 8 is a sectional view through one of the end bearings of the knife frame of Figure 6.

The reference numeral 9 designates suitable power shafts connected with a source of power not shown. To this shaft is keyed an angle crank 10. At the outer end of the crank levers there is pivoted the links 11 and 12. A bearing 13 is provided with a lug 14 to which the end of the links 11 and 12 are pivoted as clearly shown in Figure 1. This bearing member 13 is provided with a side wall 15 integrally formed therewith and with a removable side wall 16 detachably connected thereto, thereby forming between these two walls a guideway in which the guide bar 17 is mounted. Suitable antifriction rollers 18 are mounted in housings 18¹ formed on the ends of the knife bar 18² as clearly shown in Figure 4. These antifriction rollers sustain the weight of the knife bar 18² on the guide bar 17 and carry the weight of the knife bar in a balanced position. 16 are side members fastened on the opposite side of the bearing member 13 to hold the side sway of the knife bar 18².

The knife bar 18² is provided with a series

of ribs 19 extending from end to end of the bar and in substantial parallelism with each other, which ribs function as beams to rigidify and strengthen the knife bar 18². To further rigidify and to strengthen the knife bar 18² I provide ribs 20 extending transversely of the bar and between the beams 19, these ribs extending down to the lip 21 of the bar. 22 are the knife blades secured to the bar by suitable means such as the screws 23. While this knife may be in one piece, at the same time I prefer to use three separate blades, as shown in the drawings, in order to facilitate the 65 sharpening and repair of the blades.

In Figures 6 and 7 the construction and wall of the knife bar 18² is the same as that described in connection with Figures 1 and 2, the only difference being that I have placed 70 the guide bars 17^a on edge, or at right angles to the position shown in Figures 1 and 2, and the antifriction roller 24 (shown in Figure 8) is provided in this arrangement.

The knife blades 22 are each 44 inches long 75 and are placed end to end and will coast down the bars 17 through a piece of timber 12 inches wide by 9 feet long, and by the elimination of a pressure bar, all the power that is needed is the raising of the bar, whereas in all other machines cutting 62 to 100 inches would require from 50 to 70 H. P. to do the same work.

In my machine, by reason of the knife bar organization shown, the knife can be operated to cut a piece of timber 12 inches wide with a 80 power of 6½ H. P. From this it is very easy to draw a comparison as to the tremendous strain that the old machines exert on the timber to do their cutting, and from this it can be readily understood why these 85 older machines crush the grain. In all machines that I am aware of doing this kind of work the knives do not cut through all of the fiber because of the lack of shear and this fiber gathers over the edge of the knife 90 and is then pushed through the timber breaking the grain and the other fibers ahead of it, and as a consequence the stock that comes out is very pliable and shattered.

The extreme low degree on which my improved knife bar organization operates enables me to build a machine much shorter and at less cost to do away with the pressure bar usually heretofore employed to take care of

the splitting of the stock, all of which is accomplished at a much lower H. P. and results in a better product.

In the average commercial machine few of them have the draw-cut of the knife more than 45°, and most of them have not that much, but are using 60 and some of them 70°.

The average commercial machine of this character which weighs 28 tons with a capacity for 108 inch stock and the knife bar weighing about 2½ tons, as compared with my machine which weighs only about 9 tons while the knife bar weighs 1900 pounds, with a speed of 40 strokes per minute as compared with the 30 strokes per minute of the older machines now on the market, and this is all due to the knife bar organization shown and described herein.

From the above it will be seen that the angle of cutting is a very important consideration, and I have been able to utilize the desired angle of cutting without increasing the size of the machine, or the cost of the machine, and at the same time am enabled to run the machine at a materially less H. P.

In the machines in commercial use my knife is set at an angle of 30°, which is more than any other machine on the market that I know of; but, of course, it will be understood that I do not limit myself to this angle, whether the knives are cutting on the bottom of the block or on the side of the block.

Changes may be made in the detail of construction without departing from the spirit of my invention, or the scope of the appended claims.

What I claim is:

1. A knife bar comprising a main body adapted to receive knife blades, and obliquely

disposed slide bearings integral with each end of the bar, said bearings being disposed on the same angle and in parallel planes.

2. A knife bar comprising a main body, obliquely disposed slide bearings integral with each end of the bar, said bearings being disposed on the same angle and in parallel planes, and guide bars mounted in said bearings.

3. A knife bar comprising a main trussed body adapted to receive knife blades, and obliquely disposed slide bearings integral with each end of the bar, said bearings being disposed on the same angle and in parallel planes.

4. In a wood cutting machine, a knife bar comprising a main body, knives secured to said body, obliquely disposed slide bearings integral with each end of the bar disposed on the same angle and in parallel planes, guide bars mounted in said bearings, and means to operate the bar.

5. In a knife bar, a main body, an obliquely disposed anti-friction bearing integral with each end of the body both disposed in the same direction and in parallel planes and a guide bar mounted in each of said bearings.

6. A knife bar comprising a main body, a slide way bearing integral with each end of the body and open at one side, and obliquely disposed in the same angle and in parallel planes, bearings at each end of said ways, a removable side plate closing the open side of said ways back of said plate, a guide bar mounted in each of said ways and means to connect said bar to a source of power.

In testimony whereof I affix my signature.

JAMES E. ECKERSLEY.
